J. BELLOCCHIO

TOY GUN

Filed May 24, 1923

UNITED STATES PATENT OFFICE.

JOHN BELLOCCHIO, OF NEW YORK, N. Y.

TOY GUN.

Application filed May 24, 1923. Serial No. 641,062.

To all whom it may concern:

Be it known that I, JOHN BELLOCCHIO, a citizen of the United States, residing at New York city, borough of Manhattan, in 5 the county of New York and State of New York, have invented certain new and useful Improvements in Toy Guns, of which the following is a specification.

This invention relates to games and toys 10 and has particular reference to a toy weapon such as a gun, cross bow, or catapult.

Among the objects of the invention is to provide an improved construction of toy gun with respect to a number of details of 15 mechanism including a novel catch or trigger device, a part of which is in combination with a follower or plunger so designed as to serve to eject and propel an arrow or dart and also to fire a percussion cap or 20 other noise producing device.

With the foregoing and other objects in view the invention consists in the arrangement and combination of parts hereinafter described and claimed, and while the invention 25 is not restricted to the exact details of construction disclosed or suggested herein, still for the purpose of illustrating a practical embodiment thereof reference is had to the accompanying drawings, in which 30 like reference characters designate the same parts in the several views, and in which—

Figure 1 is a plan view with the follower in forward idle position.

Fig. 2 is a vertical longitudinal section 35 of the same on the line 2—2.

Fig. 3 is a partial section on the same plane as Fig. 2, but indicating the retracted or set position of the parts.

Fig. 4 is a vertical transverse section on 40 the line 4—4 of Fig. 2.

Referring now more specifically to the drawings I show my improved toy gun as comprising a main rib or barrel portion 10 extending the full length of the device from 45 the muzzle to the butt. This rib may be of any suitable material or cross sectional design, but is indicated as provided with a vertical longitudinal slot 11 formed centrally along its mid portion. 12 indicates

50 an arm rest of any suitable construction connected rigidly to the butt end of the rib 10. To stiffen this construction the arm rest is provided with a tenon 13 fitted into a notch 14 in the end of the rib.

55 The follower above alluded to comprises a finger piece 15 and a plunger 16. The

finger piece is in the nature of an angularly formed block, the top portion of which is fitted loosely in and slideable along the slot 11. This finger piece is held from vertical 60 displacement by a cross pin 15'. The front lower portion of this finger piece is curved at 17 for easy application of the operator's finger in drawing the follower rearward to set or locked position, and the rear lower 65 portion thereof is extended backward at 18 so as to engage beneath that portion of the rib at the rear end of the slot, thereby stabilizing or steadyng the device in practice. The plunger 16 is longer than the slot 70 and operates directly over the slot, one end at least of the plunger always resting upon the top surface of the member 10. In normal position both ends lie against the top of the rib. The follower includes also 75 a hammer portion 19 constituting in effect an upward and forward projection from the front end of the plunger to which and the finger piece it is connected rigidly. The rear end of the hammer is provided with a 80 notch 20 and above and in advance of the notched portion is located a cross head 21 serving two purposes, one an anchorage for the elastic power means in the nature of rubber bands 22, and as a holder for a keeper 85 23 in the nature of a wire hook extending rearward and downward over and in spaced relation to the notch. Connected also to the hammer portion just in front of the cross head is a combined sight and guard 90 24 fixed in erect position transversely of the device. The elastics 22 extend beneath the lower corners of the guard as well as around and beneath the cross head.

Near the muzzle end of the rib 10 is fixed 95 a lug 25 around which the forward portion of the elastics 22 is engaged. This lug as well as a cover plate 26 is secured in spaced relation to the rib 10 by means of a pair of beads or strips 27 extending normally the 100 full length of the rib and spaced from each other on opposite sides of the vertical center thereof, forming a guide way communicating with the slot 11 and along which the plunger 16 operates.

At the rear end of the cover plate 26 is fixed a rigid relatively heavy anvil 28 and in which is formed a notch 29. This anvil may be formed of metal or the bottom of the notch may be faced with metal at 30 if the 110 anvil is formed of a cheaper material. Likewise the forward or nose end of the hammer

19 may be faced with metal at 31 for co-operation with the bottom of the notch for firing a percussion cap or the like when the device is discharged under the force of the 5 elastics 22.

Toward the rear or stock portion of the gun I provide a cover plate 32 forming with the beads 27 a guide way 33 for the rear end of the plunger. At the front end of this 10 cover plate 32 is a fulcrum member 34 in a central opening 35 of which is fitted at 36 a peculiar form of trigger member having a forwardly and downwardly projecting hook 37 and a rearwardly and downwardly 15 projecting thumb piece 38 urged normally upward by a leaf spring 39 so that the point of the hook 37 will ride up over the bevel 20 of the notch 20 and thence downward into the notch 20 of the hammer when the latter is drawn 25 rearward to set position as in Fig. 3. The keeper 23 engages over the top of the hook and serves to prevent, in co-operation with the leaf spring 39, the premature release of 30 the follower. The keeper, however, is sufficiently resilient to permit the trigger to be drawn from the notch 20 when the thumb piece is depressed. The front end of the 35 fulcrum member is notched at 41 to receive the beveled rear end of the hammer in set position.

40 42 indicates an arrow, dart, or other projectile shown as attached by means of a line 43 to the muzzle end of the gun for retrieving it after it is discharged.

45 The side edges of the rib 10 are notched at 44 and 45 for the operator's thumb and fingers of the hand in which he holds this part of the device both for setting the plunger and for holding the device while shooting.

50 After the follower is drawn back to set position against the force of the elastics 22 as in Fig. 3, the projectile is inserted into the muzzle end of the guide way between 45 the beads 27 and below the cover plate 26, going toward or against the front end of the plunger 16. A percussion cap may then be inserted in the notch 29 of the anvil.

With the device now held as indicated for shooting the operator's right thumb will 55 come naturally over the thumb piece 38 and after suitable aim is taken, using if desired a small peep hole 46 in the guard 24, the 60 toy weapon is discharged by pressure of the thumb as stated, setting free for forward impulse the follower, the projectile 42 being delivered forcibly and at the same 65 time the percussion cap being fired by the anvil. The operator's hands and face are 70 protected from the flash of the percussion cap by means of the guard 24, lying at such time close in the rear of where the flash takes place, thus insuring that the only flash 75 can take place forward or directly laterally 80 from the anvil.

I claim:

1. The herein described toy gun comprising a barrel portion having a guide way, a follower movable along said guide way, resilient means for urging the follower forward forcibly, the follower including a notched member having a resilient keeper spaced thereover, a fulcrum member having a notch at its forward end, and a trigger means including a member pivoted between 75 its ends upon said fulcrum member, one end of the trigger co-operating with the first mentioned notched member and held in engagement by said keeper, while the rear end of the trigger member is manually operable for releasing the follower, the notched end of the follower extending into the fulcrum member notch, substantially as set forth.

2. The herein described toy gun including 85 a slotted rib member, a follower movable along said slot, elastic means connected with the follower for driving it forward forcibly when released, said follower including a hammer having a notch in one end and an 90 upwardly projecting guard toward its other end, said guard having a peep hole formed therethrough, and an anvil co-operating with the hammer in front of said guard.

In testimony whereof I affix my signature. 95
JOHN BELLOCCHIO.
